LIQUID DISPENSING SYSTEM

Arthur Gordon Wheeler and Martin J. Roznowski,
Syracuse, N. Y., assignors of one-half to Sidney A. Scobell, Syracuse, N. Y.

Application September 6, 1938, Serial No. 228,555

2 Claims. (Cl. 225—12)

This invention has for its object a system for dispensing liquid, as beverages, and particularly beer, and the like, and cleansing the pipes and coils through which the beer passes without wasting or fouling the beer or without mixing the beer and the cleansing fluid.

It further has for its object a system which is simple and economical to install, maintain and operate and which can be operated by one with no mechanical knowledge, such as bar-tenders and the like, without danger of damage or loss resulting from unskilled or improper operation.

It further has for its object a system which is hydraulically operated with means for holding the system in its operated position, in case the water pressure fails, especially while the cleansing fluid is standing in the dispensing coils for a long period, as over night, while no one is in attendance.

It further has for its object a system in which there is no mixing of the beer and cleansing fluid or contaminating of the beer, if the operator or bar-tender should operate the cleansing fluid valve immediately after the operation of the valve which controls the operation of cutting on and off the beer from the coils or if the operator should open the cleansing valve before operating the control valve for the beer.

The invention consists in the combinations and constructions and novel features hereinafter set forth and claimed.

In describing this invention, reference is had to the accompanying drawings in which like characters designate corresponding parts in all the views.

Figure 1 is a diagrammatic view of a dispensing system embodying this invention.

Figure 2 is a longitudinal sectional view of the retarding valve in the cleansing fluid system.

Figure 3 is a sectional view of the control valve.

Figure 4 is a sectional view on line 4—4, Figure 3.

Figure 5 is an elevation of the two-way valve on the tap rods for controlling the flow of beer from the barrels.

Figure 6 is a sectional view on line 6—6, Figure 5.

The system is applicable for one or more reservoirs or barrels and that here shown is for four barrels of liquid or beer to be dispensed.

1 designates the barrels which are usually located in the basement under the bar room. 2 is the so-called tap rod; 3 the conduits including coils 4 between the tap rods and the dispensing faucets 5, the coils and faucets 5 being located

on or adjacent the floor 6 of the bar room above the basement.

The invention consists of a hydraulically-operated two-way valve in the conduit or between the reservoir or barrel and the dispensing faucet and near the reservoir or barrel and operable into two positions, into first position to open the conduit through the coil to the faucet, to the flow of beer from the barrel, and into second position to cut off the flow of the liquid or beer from the barrel, a water pressure system for operating said valve including branch conduits, hydraulically-operated motors in the branches for operating the two-way valve from either position to the other, and a control valve connected in the water pressure system operable into first position to open one branch to the flow of water to the motor in that branch and to open the other branch to the outflow or discharge of water therein, and into a second position to effect the flow of water through the second branch through the motor therein, and open the second branch to the outflow or discharge of water, a cleansing fluid conduit connected to the two-way valve to be closed thereby when the two-way valve is in its first position and opened when the two-way valve is in its second position, and a control valve in the cleansing fluid conduit.

The invention further includes means for retarding the flow of the cleansing fluid through its conduit for a predetermined time, in order that the two-way valve may have time to move from first to second position in case the cleansing fluid control valve is operated too soon after the control valve in the hydraulic system is operated, or in case the cleaning fluid control valve is operated prior to the operation of the control valve in the hydraulic system, this being a precaution against the mixing of the water with the beer.

The invention further consists in means for holding the two-way valve in its operated position, in case the water pressure fails in the hydraulic system, especially when the two-way valve is in second position, that is, the position assumed when the beer is off or held in the barrel.

There is a two-way valve for each conduit 3, this valve being located adjacent the barrel 1 or at the upper end of the tap rod 2, which valve is normally in first position or position occupied when the beer is free to flow under the pressure in the barrel through the pipes 3 and coils 4 to the faucet, and is operable into second position to cut off the conduit 3 to the flow of beer from the barrel 1, and when in second position, is open to cleansing fluid, the flow of which is

normally cut off by the two-way valve when in first position, these valves being hydraulically operated through branch pipes, and a control valve operable into one position to permit the flow of water under pressure, to one branch pipe to operate the two-way valve in one direction or from first to second position, and into another position to permit the water to flow through the other pipe to operate the valve from second to first position, and when in second position, opening the two-way valve, and hence the conduit 3 and coil 4 to the flow of the cleansing fluid. It will be understood that the beer is returned from the coils to the barrel in any suitable manner prior to the cleansing operation or prior to the operation of the two-way valve into second position to cut off the flow of beer from the barrel to the conduit 3.

The cleansing conduit is connected in the water system and also has a control valve therein. Preferably, additional means, as a precaution against the mixture of beer and water, is provided, this means consisting of a retarding valve for retarding the flow of cleansing fluid after the cleansing fluid control valve is opened until a predetermined time elapses, and also holding the cleansing fluid conduit closed in the event the control valve in the hydraulic system has not been operated.

7 designates the two-way valve, this including an outer body 8 formed with piston chambers 9, 10 at its opposite ends and with intermediate transfer chambers 11, 11^a. The transfer chambers 11, 11^a are separated by a hollow partition 13 therein communicating with a nipple 12 to which each pipe 3 is coupled and communicating through ports 14 and 15 with the inner ends of the transfer chambers 11, 11^a respectively. The valve further includes a movable member including valve heads 16 and 17 in the transfer chambers 11 and 11^a and coacting respectively with valve seats 18 and 19 on the hollow partition, the valve heads being connected together by a rod 20. The valve heads are connected to pistons 21, 22 in the piston chambers 9 and 10 respectively by rods 18^a and 19^a. The chamber 11 is provided with a nipple 23 for connection to the tap rod 2 and the chamber 11^a with a nipple 24 for connection to the cleansing fluid conduit or a branch thereof. Each of the piston chambers 9, 10 is provided with a coupling 25 for connection in the hydraulic system. The pistons and piston chambers are hydraulically-operated motors.

The piston chambers 9, 10 are connected by a by-pass 26 so that movement of one piston under the pressure of the hydraulic fluid toward the inner end of its chamber 9 or 10 forces any water that has accumulated in advance of the piston through the by-pass 26 into the other piston chamber in which the piston is receding, past the cup-shaped piston packing of the receding piston. It is thought that this by-pass 26 merely becomes loaded with water, and thereafter prevents additional accumulation of water, regardless of whether or not there is any excess water to be pushed by the cup-shaped piston packing of the receding piston.

The hydraulic system consists of branch water pipes 27 and 28 connected respectively through conduits 29 and 30 to the piston chambers 9 and 10 respectively of each two-way valve 7, a control valve 31 connecting the branches 27 and 28 in a feed pipe 32 and a check valve 33. The control valve 31 is operable from first or so-

called "beer on" position to second or "beer off" position.

In Figure 3, the control valve is shown as in "beer off" or second position. However, in Figure 1, the handle of the control valve is in its position occupied when in "beer on" position. The control valve 31, as seen in Figure 3, comprises a suitable casing 34 and a movable or rotary member 35 in the casing having a handle 36. The casing is formed with nipples 37 and 38 for connection to the branch pipes 27 and 28 respectively and with the nipple 39 for connection to a pipe 40 in which is located the check valve 33 which is connected to the feed pipe 32 through a pipe 32^a. The pipe 32 is connected to the city water pressure in the building at any convenient point. It is shown here as connected to the water line feeding the water faucet 5^a. A shut off valve 49 is inserted so that the water supply to the system can be shut off for repairs without interfering with the customer's water faucet 5^a.

The rotary valve member 35 is provided with a passage 40 extending transversely therethrough, and during rotation of the valve member 35, this passage 40 can be brought into alignment with diametrically opposite passages 41, 42 in the valve casing, communicating with the nipples 37, 39 respectively, or into a position in which the passage 40 is aligned with the passage 43, and a passage 44 communicating respectively with the nipple 38 and the nipple 39, the passage 43 communicating with the nipple 39 for the passage 42. The valve casing is also provided with a by-pass or exhaust passage 45 which communicates through a coupling 46 with a discharge or outlet pipe 47 (Figure 1). The movable valve member 35 is provided with a transfer passage 48 arranged to connect either the passage 41 with the discharge passage 45 or the passage 43 with the discharge passage 45 in accordance with the position of the valve member 35 in first or "beer on" or second or "beer off" position. The valve member 35 is, as seen in Figure 4, tapered or conical and is thrust in the complementally tapered bore of the casing by a spring 50 interposed between one end of the rotary valve member 35 and a plug 51 threading into the casing 34 axially with the rotary valve member 35. The rotary valve member 35 is provided with an axial shank 52 on which the handle 36 is mounted.

When the two-way valve 7 is in first or "beer on" position, the by-pass 45 connects the passage 41 with the outlet nipple 46 permitting water from the branch 27 to discharge or exhaust therefrom. When the valve 7 is moved to "beer off" position, the valve member 35 occupies the position shown in Figure 3, in which the by-pass 45 connects the passage 43 with the discharge coupling 46 permitting the water to exhaust from the pipe 28 while the pressure is passing through the pipe 27 and actuating the two-way valve 7 into second position, or the position shown in Figure 5.

The check valve 33 may be of any suitable form, size and construction, and is for the purpose of holding the pressure in the pipe 27 or 28 in accordance with the position of the control valve 31 in case the water pressure through the feed pipe 32 drops or fails. In some cities, the water pressure drops during the night due to the fact that the water is stored in reservoirs.

53 designates the cleansing fluid conduit, this being connected to the water pipe 32 or in the pipe 32^a through a control valve 54 and coupling 75

55. The control valve 54 is an ordinary one-way or shut-off cock and is provided with a suitable handle 56. The two control valves 31 and 54 are located on the bar or adjacent the bar and adjacent each other. The cleansing fluid conduit also includes a manifold consisting of a pipe or header 57 having a tank 58 therein for chemicals, and branches 59 leading from the header 57 to each of the valves 7 or the nipples 24 thereof. Means 5 is provided in the cleansing fluid conduit 53 for retarding the flow of cleansing fluid therein for a predetermined time after the control valve 54 is opened and preventing the flow of cleansing fluid to the two-way valve 7 until the beer control valve 31 has been operated to "beer off" position.

In the illustrated embodiment of this invention, a pressure reducing valve 60 is connected in the cleansing fluid conduit 53 and the header 57 or the tank 58 therein, for the purpose of reducing the city water pressure, so that no undue strain is placed on the block tin coils. Also, a retarding valve 61 is here shown as connected between the pressure reducing valve 60 and the header 57 or the tank 58. The retarding valve 61 is the slow moving valve shown in Figure 2 which prevents opening of the header 57 or the tank 58 to the reception of the cleansing fluid from the conduit 53 until after the beer control valve 31 has been operated to second or "beer off" position. This is for the purpose of avoiding contamination of the beer by cleansing fluid, in case the operator either opens the valve 56 before he operates the control valve 31 to "beer off" position or operates the control valve 56 at the same time as or immediately after he operates the control valve 31 to "beer off" position. The pressure reducing valve 60 may be of any suitable form, size and construction, and as the operation of pressure reducing valves is old and well known, detail description thereof is thought to be unnecessary.

The retarding valve 61, as seen in Figure 2, comprises a tubular casing 62 having a nipple 63 between its ends which communicates through the pipe 53^a with the tank 58. It is provided with a coupling 64 at one end coupled to the output end of the pressure reducing valve 60 and with an outlet coupling 65 at its other end having a small outlet or bleeder passage 66 communicating with the nipple 67 which in turn communicates with a bleeder pipe 68 which communicates at 69 with the branch 28 of the hydraulic system, this being the branch that is discharging when the two-way valve 7 is operated or being operated into second position, that is, "beer off" position, or in a position shown in Figure 5.

The retarding valve also includes a movable piston or plunger 70 movable in a tubular barrel 71 located in the casing 62, the barrel 71 having an annular series of outlet passages or perforations 72 aligned with the nipple 63 and with an annular chamber 73 formed in the casing 62 around the barrel 71. The plunger 62 has piston heads or packings 74 and 75 at its opposite ends which coact with valve seats at 76 and 77 on the couplings 64 and 65 respectively.

When the cleansing fluid control valve 54 is operated to "on" position, the water passes through the pipe 53 through the coupling 64 against the end of the piston 70 and forces the piston or plunger 70 to the left, but due to the small bleeder passage 66 and conduit 68, its movement to the left is retarded, it being understood that the branch pipe 28 has water therein, which

discharges through the outlet pipe 47 from the beer control valve 31. Hence, the plunger or piston 70 moves apparently slow to the left and when it uncovers the perforations or outlets 72 in the barrel 71, the cleansing fluid is then free to flow through the passage 53^a to the chemical tank 58, header 57, pipes 59, two-way valve 7, which is now in the position shown in Figure 5, up through the pipes 3 and coils 4 to the faucets 5, providing it be necessary to open the faucets 10 until the cleansing fluid has filled the coils. In case the control valve 31 has not been turned to "beer off" position, the plunger 70 is in closed position (Figure 2) and is held from opening movement because the pipe 28 is under pressure 15 and not open to the exhaust of water therefrom.

Before the cleansing operation, the beer is returned to the barrel in any suitable manner, and is here shown as returned by air pressure through an air supply pipe 78 (Figure 1) having 20 a suitable valve 79 therein, this being connected to the coils 4 adjacent the faucet. By opening the valve 79, air pressure from the pipe 78, which is greater than the pressure in the barrel 1, while the two-way valve 7 is in first or "beer on" position, forces the beer into the coils 4 and pipes 3 back into the barrel. The air conduit 78 has branches, as 80, each branch communicating with two coils 4 through a check valve, as 81, this being a double check valve, and operates to 30 prevent beer leaking from one coil 4 to another, when the bar is being operated normally.

The check valves 81 are preferably what are known commercially as Thomas valves. As an additional precaution, a check valve 82 is interposed between the check valve 81 or the coupling 80 and the air pipe 78.

The beer in the barrels is kept under a predetermined pressure in the usual manner through pipes 83 connected to the pressure pump forming 40 part of the bar equipment.

In operation, with the control valve 31 in first or "beer on" position, and hence the two-way valve 7 in first or "beer on" position, the valve 79 in the air conduit is opened to permit the air pressure to force the beer in the coils 4 and pipes 3 back into the barrel. When the beer has been returned to the barrel, the air valve 79 is closed. Then the control valve 31 is moved from first position to second position, or from "beer on" position to "beer off" position. This operation opens the pipe 27 to the flow of water and opens the pipe 28 to the discharge of water through the bypass 45 of the valve 31 and drain pipe 47. The water passing through the pipe 27 passes through the branch 29 to the piston chambers 9 at the left hand end of the two-way valves 7 operating the movable members of the two-way valves into the position shown in Figure 6, thus cutting off the flow of beer from the tap rods 2 and opening 50 the pipes 3. In the normal operation, the cleansing fluid control valve 54 is then opened, permitting cleansing fluid to pass through the pipe 53, chemical tank 58 and header 57 into the pipes 59 into the two-way valve, through the nipple 65 55 24, thence through the port 14, nipple 12 and up into pipes 3 and coils 4, the faucets 5 being left open to permit this flow. During the flow of cleansing fluid through the pipe 53, its flow is being retarded either by the pressure reducing valve 70 60 or the retarding valve 61 or both, providing a time element within which to let the two-way valve 7 assume its position shown in Figure 5, in case of a quick successive operation of the control valves 31 and 54, or in case the valve 54 75

75

is operated in advance of the beer control valve 31, the flow of cleansing fluid through the pipe 54 is prevented by the retarding valve which is locked closed because the water can not pass through the bleeder passage 66 for the reason that the full hydraulic pressure is in the conduit 28.

The pipes and coils may be flushed out quickly or the water allowed to stand in them over night. At the end of the cleansing operation, the faucets 10 5 are opened, permitting water to flush through the pipes 3 and coils 4; then the cleansing fluid control valve 54 closed and the beer control valve 31 moved into first or "beer on" position, and the dispensing faucets 5 opened until beer commences 15 to run, the beer forcing the water or fluid in the pipes out of the pipes and coils, after the control valve 54 is closed.

What we claim is:

1. In a liquid dispensing system, the combination with a reservoir for a liquid under pressure to be dispensed, a discharge faucet, a conduit between the reservoir and the faucet, and means for returning the liquid in the conduit to the reservoir; of a hydraulically-operated two-way valve 25 in the conduit adjacent the reservoir and operable into first position to open the conduit to the flow of liquid from the reservoir and into second position to cut off the flow of liquid from the reservoir, a water pressure system for operating 30 said valve including branch conduits, motors in the branch conduits for operating the two-way valve from either position to the other, and a control valve operable into first position to open one branch to the flow of water to the motor therein 35 and open the other branch to the outflow of water and into second position to effect the flow of water through the second of said branches, and open the first branch to the outflow of water, a cleansing fluid conduit connected to the two- 40 way valve to be closed thereby when the two-way valve is in first position, and opened when in sec-

ond position, a control valve in the cleansing fluid conduit, and a retarding valve in the cleansing fluid conduit including a normally-closed member operable by the pressure in the cleansing fluid conduit to open position, and a bleeder passage connecting said valve to the branch conduit which is open to the discharge of water when the two-way valve is in second position.

2. In a liquid dispensing system, the combination with a reservoir for a liquid under pressure to be dispensed, a discharge faucet, a conduit between the reservoir and the faucet, and means for returning the liquid in the conduit to the reservoir; of a hydraulically-operated two-way valve 10 in the conduit adjacent the reservoir and operable into first position to open the conduit to the flow of liquid from the reservoir and into second position to cut off the flow of liquid from the reservoir, a water pressure system for operating 15 said valve including branch conduits, motors in the branch conduits for operating the two-way valve from either position to the other, and a control valve connected in a water pressure system operable into first position to open one branch to the flow of water to the motor therein 20 and open the other branch to the outflow of water therein, and into second position to effect the flow of water through the second branch to the motor therein and open the first branch to the outflow of the water therein, a cleansing fluid 25 conduit connected to the two-way valve to be closed thereby when the two-way valve is in first position, and opened when in second position, a control valve in the cleansing fluid conduit, and a check valve in the hydraulic system in advance 30 of the control valve in the hydraulic system for holding the pressure in the hydraulic system 35 in the event the water pressure fails.

ARTHUR GORDON WHEELER.

MARTIN J. ROZNOWSKI.
